Company, East Pittsburgh, Pa., a corporation of
Pennsylvania

Application January 26, 1939, Serial No. 252,934

12 Claims. (Cl. 80—35)

My invention relates, generally, to tensioning devices and, more particularly, to devices for subjecting a strip of material to tension as it passes between adjacent work devices.

It has been found desirable and has become common practice to subject steel strip to tension as it is passing through the reducing rolls of a strip rolling mill. This tensioning of the strip provides a drawing action in addition to the usual rolling action in the reducing rolls and thus produces a greater percentage reduction in each roll stand than is possible by the rolling action alone. In addition, the drawing action resulting from tensioning the strip as it is rolled imparts certain desirable physical characteristics to the strip steel produced.

Since a very considerable proportion of the reduction of the strip at each roll stand is due to the tension to which the strip is subjected and the amount of reduction due to tension is a function of the amount of tension, it is apparent that, all other factors being equal, the tension should be kept substantially constant to produce strip of uniform gauge.

Several methods of maintaining a substantially constant tension on the strip as it passes through the mill have been proposed, one such method maintaining the tension by current regulation of the mill motors to maintain a constant motor torque. A very successful system for maintaining a substantially constant strip tension is fully described in my copending application Serial No. 133,419, filed March 27, 1937, now Patent No. 2,189,609, issued February 6, 1940. In the system of my patent an idling roller is made to bear against the strip to deflect it from its normal pass line between the adjacent roll stands. The device so varies the transverse force acting on the strip as to maintain a substantially constant strip tension throughout a predetermined range of strip deflection. This strip deflecting or "looping" system has the advantage of permitting sudden decreases in the length of strip between roll stands without subjecting the strip to extreme tensions that may break the strip. Considerable strip breakage occurs due to this cause in rolling systems in which the strip is not looped between roll stands.

It has been found that there is a considerable variation in the thickness of the strip throughout its length as it is delivered to be rolled in the strip mill and that slight variations in the composition of the steel will cause variations in hardness throughout the length of the strip. Since the amount of strip reduction is a func-

tion of the strip tension, it follows that, if a strip of uniform gauge is to be produced, sudden changes in strip thickness and hardness may be compensated for by corresponding changes in strip tension, thus providing whatever tensions are required to reduce the parts of the strip of varying thickness and hardness to a predetermined gauge.

An object of my invention, therefore, is to provide a tensioning device for a strip rolling mill which shall function to vary the tension on the strip in accordance with variations in the resistance-to-reduction properties of the strip.

Another object of the invention is to provide a tensioning device for a strip rolling mill which shall function to provide strip tensions varying in accordance with the resistance-to-reduction properties of the strip and shall have adjustable means for producing the desired tension characteristics for a wide variety of strip thicknesses, widths and degrees of hardness.

A further object of the invention is to provide a strip tensioning device of the type which deflects the strip by the application of a transverse force thereto with adjustable means for selectively varying the tension-deflection characteristic of the device.

Another object of the invention is to provide a tension device, having a strip deflecting member, with means for selectively varying the normal range of deflection of the strip.

Still another object of the invention is to provide a tensioning device, having a strip deflecting member actuated by a lever, with means for varying the length and the normal angular displacement of the lever arms.

A further object of the invention is to provide a tensioning device, having a pivoted lever actuated strip deflecting member, with means for selectively positioning the center of gravity of the actuating mechanism to thus vary the tension deflection characteristic of the device.

A further object of the invention is to provide a tensioning device, having a strip deflecting member, with means for raising and lowering the normal range of operation of the deflecting member to compensate for the shifting of the pass line due to the substitution of reducing rolls of different diameters.

These and other objects and advantages of the invention will be apparent from the following detailed description taken in connection with the accompanying drawings in which:

Figure 1 is a perspective view of a tensioning

device embodying the principal features of the preferred embodiment of my invention;

Fig. 2 is a perspective view of an embodiment of the invention in which a different form of elevating mechanism for the tensioning device is employed;

Fig. 3 is a diagrammatic illustration of the relative positions of the tensioning device and the strip passing between adjacent roll stands;

Fig. 4 is a graph illustrating the operating characteristics of the tensioning device.

In carrying out the preferred embodiment of my invention shown in Figure 1, I provide a shaft 10 rotatably mounted upon and extending parallel to a beam member 11 which is supported between the opposing mill housings 12 and 13 of a strip rolling mill. The beam member 11 which comprises an angle iron having horizontal and vertical flanges is secured to the mill housings 12 and 13 by means of bolts 14 screw-threaded into the mill housings through slotted openings 16 in the vertical flange of the beam.

An actuating mechanism 18 is provided for imparting rotational movement to the shaft 10. An idling roller 20 extends between and is rotatably mounted upon parallel arms 22 and 24 which are secured to the shaft 10 by an adjustable coupling 26 by means of which the relative angular displacement of the arms 22 and 24 with respect to the shaft 10 may be varied. An adjusting mechanism 28 is provided for moving the roller 20 lengthwise of the arms 22 and 24 to thus vary its displacement from the shaft 10.

A pair of jacks 30 and 32 are provided for simultaneous operation actuatable by the adjusting mechanism 34 for raising or lowering the beam member 11 upon which the entire tensioning mechanism is mounted.

A pair of shiftable weight members 36 and 38 is provided for varying the center of gravity of the mechanism to provide variations in the operating characteristics of the tensioning device.

A regulator control unit comprising a synchro-tie transmitter 40 by which a remotely positioned regulator for the mill motors is actuated after the manner described in detail in the copending application of W. G. Cook Serial No. 165,287 filed September 23, 1937, now Patent No. 2,242,346, issued May 20, 1941, and having a common assignee with the present application, is mounted upon the horizontal flange of the beam 11. The synchro-tie transmitter 40 is connected to be actuated by the shaft 10 through a clutch mechanism, indicated, so that the relative angular displacement between the synchro-tie mechanism and the regulator actuated thereby and the shaft 10 may be varied.

The embodiment of the invention shown in Fig. 2 is similar to that of Fig. 1 except in the manner of mounting the mechanism in operative position and similar reference characters designate corresponding parts of the two embodiments of the invention. The tensioning mechanism in this embodiment of the invention is hingedly mounted, as shown, upon upright members 42 and 44 which are supported by auxiliary beam members 46 and 48 which extend between the opposing mill housings of adjacent mill stands of the strip mill. The vertical adjustment of the mechanism is provided by screws 30' and 32' which are screw-threaded into a lower flange of a beam member 11' upon which the mechanism is mounted and engage the auxiliary beams 46 and 48.

In Fig. 3 of the drawings there is shown dia-

grammatically the relative positions of some of the operating parts of the tensioning mechanism with respect to the strip as it passes between adjacent roll stands.

Referring to Fig. 1 for a more detailed description of the preferred embodiment of my invention, the shaft 10 is supported by bearing members 50 and 52 which are mounted upon the horizontal flange 54 of the beam 11. The operating mechanism 18 for the shaft 10 comprises a lever arm 56 which is secured to the shaft and extends substantially horizontally therefrom. A roller member 58 is rotatably secured to the end of the arm 56 and is positioned between the spaced horizontally disposed ends of an opening in a collar member 60. The upper end of the opening in the collar member 60 is connected by means of a piston rod 62 to an actuating cylinder 64 similar to that described in my hereinbefore referred to patent. The lower end of the opening in the collar member 60 is connected by a piston rod 66 to a suitable damping cylinder 68 which is provided for preventing too sudden movements of the tensioning mechanism.

The piston rods 62 and 66 and the collar member 60 may be constructed integrally or may be made separately and rigidly secured together in any suitable manner as a unitary rod extending between pistons not shown, operating in the cylinders 64 and 68. The rods 62 and 66 are suitably guided between roller members 67 best shown in Fig. 2.

The actuating cylinder 64 and the damping cylinder 68 are mounted upon a plate member 70 which is suitably secured to the beam member 11 and extends substantially normally therefrom.

A sleeve member 72 is rotatably mounted upon the shaft 10 upon the bearing members 50 and 52, and has the crank arm means or members 22 and 24 secured thereto in any suitable manner and extending substantially normally therefrom. The coupling means 26 comprises a bracket 74 secured to the arm 22 and rotatably supporting a worm 76 which cooperates with a worm gear segment 78 secured to the shaft 10. The worm 76 may be actuated by a handwheel 80 to thereby rotate the sleeve 72 and the tensioning roller supported thereby with respect to the shaft 10.

The tensioning roller 20 is supported in a bearing member 82 which is slidable in a slot as shown in the arm 22 and a similar bearing member, not shown, in the arm 24. Plate members 83 and 84 are secured to the ends of the arms 22 and 24 to limit the movement of the tensioning roller bearings on the arms 22 and 24. A screw member 85 threadedly engages a worm wheel 86 and bears against the bearing member 82 to provide longitudinal movement of the bearing 82 upon rotation of the worm wheel 86. The bearing 80 supporting the other end of the roller 20 in the arm 24 is likewise adjustable by a worm wheel 88 mounted on the arm 24. A shaft 90 extends between the arms 22 and 24 and has connected thereto within the arms 22 and 24 worms, not shown, engaging the worm gears 86 and 88, and has an operating handwheel 100 mounted upon one end thereof. It will be seen that actuation of the handwheel 100 will thus cause longitudinal movement of the roller member 20 in its supporting arms 22 and 24.

The weight members 36 and 38 are mounted upon arms 102 and 104, respectively. The arm 102 extends substantially vertically downward from the lever arm 56 and the arm 104 extends substantially horizontally from and in the op-

posite direction to the lever arm 56. Suitable adjusting means are provided for adjustably positioning the weights 58 and 38 at any desired point along their supporting arms 102 and 104.

When it is desired to adjust the relative positions of the shaft 10 and the regulating means controlled by the synchro-tie transmitter 40, the clutch may be thrown out of engagement by means of the handle 105, and the adjustment of the regulating system made by operating the synchro-tie 40 by a suitable handwheel 106. With this adjustment completed, the system may be placed into normal operation again by actuation of the clutch to engagement by the operating handle 105.

The jacks 30 and 32 comprise base members 108 and 110 supported on suitable bracket members 112 and 114 on the mill housings 12 and 13 and screw-threaded shafts 116 and 118 fixed to these base members 108 and 110, respectively. Worm gears 120 and 122 are threadedly engaged with the shafts 116 and 118 and bear against plate members 124 and 126 which in turn engage plate members 128 and 130 mounted upon the horizontal flange 54 of the beam 11. Worms 132 and 134 are mounted for rotation on brackets 136 and 138 secured to the plate members 128 and 130. A shaft 140 operable by a handwheel 142 is connected to simultaneously actuate the worms 132 and 134. Thus, to adjust the vertical displacement of the entire mechanism, the bolts 14 may be loosened to permit freedom of movement of the beam 11 and the handwheel 142 actuated to provide the desired adjustment of the mechanism. When the desired adjustment has been made, the bolts 14 may be tightened to secure the mechanism in the desired position.

Referring to Fig. 2, a plate member 144 is secured to the beam 11 and arms 146 and 148 are secured in any suitable manner to the plate members 10 and 144, respectively, and extend substantially horizontally therefrom as shown. The arms 146 and 148 are suitably pivoted on the upright arms 42 and 44. The screws 30' and 32' extending through the bottom flange 150 of the beam 11' are held in position by the lock nuts 152 and 154 and bear against the auxiliary beams 46 and 48 to hold the tensioning mechanism in position. When it is desired to change the vertical displacement of the tensioning mechanism, it is only necessary to loosen the lock nuts 152 and 154, actuate the screws 30' and 32' to raise or lower the beam 11' as desired and to tighten the lock nuts 152 and 154 when the desired adjustment has been made. The part of the beam supporting the clutch mechanism and the synchro-tie transmitter discussed in connection with the embodiment of the invention shown in Fig. 1 has been broken away in Fig. 2 to better illustrate the mechanism of Fig. 2.

In the operation of the device, the actuating cylinder 64 will operate upon the arm 56 and transmit through the arms 22 and 24 to the tension roller 20 a force which will deflect the strip from its normal pass line between the adjacent roll stands as indicated diagrammatically in Fig. 3. In Fig. 3 the tensioning roll 20 is shown in the normal strip tensioning position and in the extreme upper and lower positions of its operating range. Tensioning roller 20 may be kept within this operating range by regulating devices controlled by the synchro-tie transmitter 40 shown in Fig. 1 which regulating devices may take the form shown in either my hereinbefore referred to patent or the hereinbefore referred

to patent to W. G. Cook. With the arms 22, 24 making an angle of substantially 51°, with the extension of the lever arm 56 and a substantially constant pressure applied to the arm 56 by the operating cylinder 64, a substantially constant tension will be applied to the strip by the tensioning roller 20 as described in my hereinbefore referred to copending application.

The curve A of Fig. 4 illustrates the functioning of the device under these conditions. With the range of deflection above the pass line between 3½ inches and 5½ inches indicated by the points M and N on the curve, it will be seen that there is very little variation in strip tension throughout this range of strip deflection. This operation is suitable where the strip is of uniform thickness and hardness, and uniform constant tension on the strip will produce a uniform thickness of finished product.

However, some of the strip material as it comes through the mill may have thick portions and/or relatively hard and soft portions requiring greater or less degrees of tension to produce the different degrees of reduction necessary in such sections of the strip which will result in a uniform final strip thickness. When a hard section or a thick section comes through the mill, for instance, since the degree of reduction of the strip is a function of the amount of tension upon the strip, it is desirable to increase the tension on the strip. As the hard section or thick section comes through the mill there will be less reduction in the reducing rolls and the amount of strip between adjacent rollstands will be less thus decreasing the deflection of the strip by the tensioning roll 20. Where these conditions exist, it is desirable therefore to have a strip tension-deflection characteristic which will give a rising tension in response to decreased deflection of the strip. This characteristic is produced by actuating the angle adjusting coupling 28 by operation of the operation handle 80 as hereinbefore described to decrease the angle between the arms 22 and 24 and extension of the arm 56, that is, decrease the angle between the arms 22 and 24 and the normal pass line. With this decrease in the operating angle of the arms 22 and 24, it will be necessary to lower the mechanism if it is desired that the tension roller 20 operate within the same deflection range. This may be done by the actuation as hereinbefore described of the jacks 30 and 32 in the device of Fig. 1 and the screws 30' and 32' in the device of Fig. 2.

The tension-deflection characteristic of the device when the tensioning roll arm angle has been decreased is illustrated by the curve B of Fig. 4.

It will be seen by reference to this curve that when a hard section of the strip is encountered, the decreased deflection caused thereby will result in increased tension in the strip, to thus produce the necessary increased strip reducing force necessary to produce strip of uniform gauge.

If it is desired to vary the "flatness" of the tension-deflection characteristic curve of the device, it is only necessary to vary the displacement of the tensioning roll 20 from the shaft 10 by operation of the handwheel 100 to actuate the adjusting mechanism 28 as hereinbefore described. Thus by shortening the distance between the tensioning roller 20 and the shaft 10, thereby making the effective angle arm of the arms 22 and 24 shorter, a tension-deflection characteristic curve indicated by curve C of Fig. 4 may be produced. It will be seen that a slightly higher tension throughout will be produced by this

change in the tensioning roller lever arm length and that a slightly rising tension characteristic will be produced at the extreme limits of the deflection range. Here again the vertical displacement of the actuating mechanism will have to be changed if the same range of deflection is desired.

The "flatness" of the tension-deflection characteristic curve may also be controlled by the horizontal adjustment of the weight 38 on its supporting arm 104. Thus by moving the weight 38 away from the shaft 10 the flatness of the characteristic curve is increased as illustrated by curve D in Fig. 4. By moving the weight 38 to the right, the center of gravity of the whole mechanism is moved to the right and a part of the force exerted by means of the actuating cylinder 64 will have to be used in overcoming the increased torque applied to the system by the movement of the weight 38 further from the axis of rotation of the tensioning device. Thus a smaller actuating force will be applied to the tensioning roller 20 and decreased tension throughout the tensioning range will be produced as indicated by curve D.

A change in the tension-deflection characteristic curve similar to that caused by the decrease in the tensioning roll actuating arm angle may be produced by an increased downward displacement of the weight 36 on its supporting arm 102. It will be seen that the weight 36 adds to the effective tensioning torques applied to the tension roll 20 when the strip is below its normal position, since the weight 36 will then have moved in a clockwise direction, as viewed in Fig. 3, and will add to the turning movements acting upon the tensioning roller 20 to deflect the strip. When the tension roll 20 is above its normal position, however, the weight 36 will be moved in a counter-clockwise direction and will apply a turning moment to the tensioning system opposite to the moment caused by the pressure applied thru the actuating cylinder 64 and will thus detract from the effective strip tension in the increased strip deflection range. This effect of moving the weight 36 downward is illustrated by curve E of Fig. 4. Here it will be seen that between the extremes M and N of the range of deflection there will be a rising tension characteristic, the tensioning characteristic being raised at the lower deflections and lowered at the higher deflections.

The vertical adjustment of the tensioning mechanism is also necessary in the event of changing of reducing rolls in the mills and substituting rolls of greater or less diameter. It will be seen that this will raise or lower the normal pass line of the mill and will be necessary to raise or lower the tensioning mechanism a corresponding amount if the same range of deflection above the normal pass line is to be maintained. If it be desired that a rising tension-deflection characteristic curve be provided, the tension range may be shifted by varying the angular displacement of the synchro-tie transmitter 40 with respect to the shaft 10 as hereinbefore described. Thus, by proper adjustment of the synchro-tie transmitter, the tensioning roll may be kept within the deflection range of from 2 to 4 inches above the normal pass line and the tension-deflection characteristic will then be that indicated by the curve A between these two deflection points in the graph of Fig. 4.

This adjustment may be utilized in providing rising tension-deflection characteristics of different tension ranges for different materials to

be rolled. A thicker, wider or harder strip will require higher tensions. To provide the higher tension range, the range of deflection may be changed from 3.5-5.5 inches indicated by the points M—N, with the tensioning device otherwise adjusted for the characteristics indicated by curve E, to a range 2.5-4.5 inches indicated by the points O—P.

A similar change in tension range for the purpose of providing the desired tension range for different degrees of strip thickness, width and hardness may be made by changing the tensioning roll arm angle as explained hereinbefore. Thus, if the tension-deflection characteristic indicated by curve B includes a greater tension range than is desired for the particular strip to be rolled, a characteristic illustrated by curve B' may be produced by operating the roller arm angle adjusting mechanism 26 to give a larger roller arm angle than that which will give the characteristic illustrated by curve B. It will be seen that the tension range between the points M—N on curve B' is smaller than the tension range between these points on curve B.

25 This same variation of tension range of rising tension characteristic may be produced by variation of the position of the weight 36 as hereinbefore explained and illustrated by curve E. It may also be produced by varying the "flatness" 30 of the curves by adjustment of the tensioning roller arm length as explained hereinbefore and illustrated by curves C, or by adjusting the position of the weight 38 as explained hereinbefore and illustrated by curve D. The desired rising 35 tension-deflection characteristic would be obtained in these two cases by operating the tensioning roller in the lower deflection ranges such as, for instance, between the points O—P representing a deflection range of 2.5-4.5 inches.

40 The tension-deflection characteristic of the tensioning device may also be varied by changing the position of the tensioning device substantially horizontally with respect to the roll stands. This is indicated by the broken line 45 position of the tensioning roller 20' in Fig. 3. When the tensioning roller occupies a position substantially equally spaced from the roll stands, as indicated by the position of the roller 20 in Fig. 3, the reaction on the roller will be substantially vertical as indicated by the vector R. If, now, the tensioning device is moved to the position indicated by the roller 20', the reaction on the roller will be in the direction indicated by the vector R', displaced somewhat from the vertical. If this new roller position is established by merely shifting the whole tensioning mechanism to the left without varying its vertical elevation, roller arm length or roller arm angle, this change in the angle of the reaction 55 on the tensioning roller will have the effect of decreasing the tensioning roller arm angle with respect to the pass line, thus giving the tensioning device a rising tension-deflection characteristic as indicated by curve B of Fig. 4.

50 This horizontal adjustment of the tensioning device may most easily be made with the embodiment of the invention of Fig. 2. Additional threaded holes 45 may be provided in the auxiliary beams 46 and 48 for receiving the screws 47 which secure the upright members 42 and 44 to the auxiliary beams 46 and 48. Thus to provide a rising tension-deflection characteristic for the embodiment of the invention of Fig. 2, it is only necessary to remove the supporting screws 47 and

move the device to the position where the threaded holes 45 will receive the screws 47.

It will be seen that I have provided a strip tensioning device for a strip rolling mill which may be readily installed on existing strip mills, which is simple and efficient in operation and inexpensive to install and maintain, and which may be readily adjusted to provide any desired tension-deflection characteristic.

In compliance with the requirements of the patent statutes, I have shown and described herein the preferred embodiments of my invention. It is to be understood, however, that the invention is not limited to the precise constructions shown and described, but is capable of modification by one skilled in the art, the embodiments herein shown being merely illustrative of the principles of my invention.

I claim as my invention:

1. In a strip tensioning device for a strip rolling mill, a pivotally mounted lever, a bearing member mounted on one arm of said lever, means for applying a force to the other arm of said lever to cause said bearing member to transmit a transverse force to the strip to thereby deflect the strip and subject it to tension, and means for selectively varying the angular displacement between said lever arms to thereby vary the tension-deflection characteristics of the tensioning device.

2. In a strip tensioning device for a strip rolling mill, a pivotally mounted lever, a bearing member mounted on one arm of said lever, means for applying a force to the other arm of said lever to cause said bearing member to transmit a transverse force to the strip to thereby deflect the strip and subject it to tension, and means for selectively varying the length of the lever arm upon which said bearing member is mounted to thereby vary the tension-deflection characteristics of the tensioning device.

3. In a strip tensioning system for a strip rolling mill in which a bearing member subjects the strip to tension by deflecting the strip from its normal pass line and is kept within a limited deflection range by a regulator, a regulator control unit, coupling means for connecting said regulator control unit for actuation in accordance with the deflection of the strip by the bearing member, and means whereby the relative displacement of said regulator control unit and the bearing member may be selectively varied to thereby selectively vary the limits of the regulator-controlled deflection range.

4. In a strip tensioning device for a strip rolling mill, a pivotally mounted lever, a bearing member mounted on one arm of said lever and means for applying a force to the other arm of said lever to cause said bearing member to transmit a transverse force to the strip to thereby deflect the strip and subject it to tension, said means for applying a force to said arm comprising a collar member having an opening therein, a roller member mounted on said other arm of said lever and extending into and operably engaging the ends of the opening in said collar member, a piston rod rigidly secured to said collar member, an actuating piston and cylinder for said piston rod and guide means providing straight line motion for said piston rod.

5. In a strip tensioning device for a strip rolling mill, a beam member extending normal to the direction of travel of the strip, a shaft mounted for rotation on and substantially parallel with said beam, crank arm means extending from and substantially normal to said shaft, means secur-

ing said crank arm means for rotation with said shaft, a roller member mounted on said crank arm means for rotation about an axis substantially parallel with said shaft, means for applying a rotational force to said shaft, means mounting said beam in such a position as to cause said roller to bear against the strip as it extends between adjacent roll stands to thus subject the strip to tension by deflecting it from its normal pass line, and means for selectively varying the displacement of said beam with respect to the normal pass line of the strip to thus selectively vary the tension-deflection characteristics of the tensioning device.

6. In a strip tensioning device for a strip rolling mill, a beam member extending normal to the direction of travel of the strip, a shaft mounted for rotation on and substantially parallel with said beam, crank arm means extending from and substantially normal to said shaft, means securing said crank arm means for rotation with said shaft, a roller member mounted on said crank arm means for rotation about an axis substantially parallel with said shaft, means for applying a rotational force to said shaft, means mounting said beam in such a position as to cause said roller to bear against the strip as it extends between adjacent roll stands to thus subject the strip to tension by deflecting it from its normal pass line, means for pivotally mounting said beam on an axis substantially parallel to, spaced from, and in a horizontal plane with the axis of said roller, and means for rotating said beam about its pivotal axis thus varying the tension-deflection characteristics of the tensioning device.

7. In a strip tensioning device for a strip rolling mill, a beam member extending normal to the direction of travel of the strip, a shaft mounted for rotation on and substantially parallel with said beam, crank arm means extending from and substantially normal to said shaft, means securing said crank arm means for rotation with said shaft, a roller member mounted on said crank arm means for rotation about an axis substantially parallel with said shaft, means for applying a rotational force to said shaft, means mounting said beam in such a position as to cause said roller to bear against the strip as it extends between adjacent roll stands to thus subject the strip to tension by deflecting it from its normal pass line, an auxiliary beam extending from each of the opposing mill housings of one mill stand to the adjacent opposing mill housings of its adjacent mill stand, means for pivotally mounting said first mentioned beam on said auxiliary beams on an axis substantially parallel to, spaced from, and substantially in a horizontal plane with the axis of said roller, and means for adjustably positioning said first mentioned beam about its pivotal axis thus varying the tension-deflection characteristics of the tensioning device.

8. In a tensioning mechanism for a strip rolling mill, a shaft mounted for rotation and disposed normal to the direction of travel of the strip as it passes between adjacent roll stands, spaced parallel arms disposed substantially normal to said shaft, means securing said arms for rotation with said shaft, a tensioning roller extending between and rotatably supported by said arms, said arms being so disposed as to cause said roller to subject the strip to tension by bearing against the strip and deflecting it when rotating torque is applied to said shaft, a lever arm secured to said shaft and extending substantially normal thereto, means for applying a force to

said lever arm to thus provide the actuating torque for said tensioning roller, a pair of auxiliary arms one extending substantially vertically and the other extending substantially horizontally from said shaft and a longitudinally adjustable weight mounted on each of said auxiliary arms whereby the position of the center of gravity of the tensioning mechanism may be shifted any desired amount in any radial direction to thus vary the tension-deflection characteristics of the tensioning mechanism.

9. In a strip tensioning device for a strip rolling mill, a shaft disposed normal to the direction of the pass line of the mill, operating means for applying a torque to said shaft, a pair of arms extending away from at substantially right angles to said shaft, means securing said arms for rotation with said shaft including means for selectively varying the angular displacement of said arms with respect to said shaft, a roller extending between and supported by said arms, means for selectively varying the position of support of said roller on said arms, and means for simultaneously varying the displacement of said shaft, arms, tensioning roller and operating means from the pass line of the mill to thereby vary the tension-deflection characteristics of the tensioning device.

10. In a strip tensioning device for a strip rolling mill, a beam member extending normal to the path of travel of the strip, a shaft mounted for rotation on and substantially parallel with said beam, a sleeve member mounted upon said shaft and coaxial therewith, spaced parallel arms secured to and extending from said sleeve member substantially normal to the axis of the sleeve member, a roller extending between and rotatably mounted upon said arms, means connecting said sleeve for rotation with said shaft, said beams being so mounted with respect to the strip and

said sleeve having such a relation to said shaft as to cause said roller to subject the strip to tension by bearing upon and deflecting the strip when a rotating force is applied to said shaft, 5 said means connecting said sleeve for rotation with said shaft comprising means for selectively varying the relative displacement of said shaft and said sleeve about their common axis to thereby selectively vary the tension-deflection characteristics of the tensioning device.

10 11. In a strip tensioning device for a strip rolling mill, a bearing member, an actuating mechanism for the bearing member comprising force providing means and a force transmitting linkage connecting the force providing means in operative relation with the bearing member for causing the bearing member to bear against the strip to thus subject the strip to tension by applying a transverse force to the strip and thereby deflecting the strip from its normal pass line, 15 and means for simultaneously selectively shifting the position of said bearing member and said actuating mechanism relative to the normal pass line of the strip to thereby vary the tension-deflection characteristics of the tensioning device.

20 12. In a strip tensioning device for a strip rolling mill disposed between adjacent roll stands of the mill, a pivotally mounted lever, a bearing member mounted on one arm of said lever, a force providing means disposed to apply a force to the other arm of said lever to cause said bearing member to transmit a transverse force to the strip and thus subject the strip to tension, and 25 means for simultaneously varying the horizontal spacing of the lever, the bearing member, and the force providing means with respect to the adjacent roll stands to thereby vary the tension-deflection characteristics of the tensioning device.
